HYDRAULIC TRANSMISSION FOR PRESS RAMS

Alois Karl Nowak, Evanston, Ill.

Application August 22, 1947, Serial No. 770,033

17 Claims. (Cl. 60—52)

1

This invention relates to power presses, and has for its principal objects to make a fixed stroke drive, such as an eccentric, deliver a longer stroke to the tool carrying slide and vary that stroke to suit different die sets, to increase the number of stroke cycles per minute, and hence the output of the press; to eliminate the customary costly and cumbersome means for adjusting the "shut height" of the press and provide fine and accurate pressure control; and to provide a pressure dwelling period at the bottom of the stroke without interrupting the cycle.

Other objects and advantages of the invention will appear as the disclosure proceeds and the description is read in connection with the accompanying drawings, in which

Fig. 1 is a front elevation of a press embodying the invention, parts being in vertical section on the axes of the hydraulic cylinders;

Fig. 2 is a similar view from the rear with parts of the crown, the frame, and the slide broken away to better show the arrangement;

Fig. 3 is a similar view from the front with parts of the crown and the frame broken away to show the arrangement;

Fig. 4 is a transverse section on the line 4—4 of Fig. 1;

Fig. 5 is a vertical section through the filling and by-pass valve and the pressure limiting valve; and

Fig. 6 is a cycle curve of the press with a 6-inch stroke eccentric operating with a 4-inch draw.

General description

The press shown in the drawings includes a bed 10, upright side pieces 11, and a crown 12 forming a sort of framework suitably fastened together as by the customary tie rods.

A tool carrying slide 13 is guided within the frame between the side pieces to move up and down in each cycle of operation.

The slide is positively drawn toward its up position by pistons 14 and cylinders 15 having piston rods 16 secured to the slide. Constant air pressure or other fluid pressure in the cylinders 15 below the pistons urges the slide toward its upper position.

A motor 17 on top of the crown drives a flywheel 18 through belts 19. The flywheel is on a countershaft 20 equipped with an air clutch 21 by means of which and gearing 22 it drives the main shaft 23 having an eccentric 24 and an eccentric strap 25.

The force of the eccentric is transmitted to the slide 13 and its stroke varied by a hydraulic

transmission forming a very important part of this invention.

The hydraulic transmission (Fig. 1)

6 The eccentric strap 25 drives a ram 26 in a main cylinder 27 having a main piston 28 extending through a stuffing box 29 in the lower end of the cylinder opposite to the ram 26. The connection between the strap and the ram includes a wrist pin 30. In the interests of compactness, the ram is made hollow, as indicated at 31, to receive the upper portion of the piston 28 in the telescoping relation indicated in the drawing.

10 15 Associated with the main cylinder are auxiliary cylinders 32 and 33, one at each side of the main cylinder and each equipped with a piston 34 extending through the corresponding stuffing box 35 in the lower end of the cylinder. All of the cylinders are made fast in the bottom of the crown 12, as diagrammatically illustrated at 36.

The ram 26 has a cross-sectional area equal to the sum of the cross-sectional areas of the pistons 28 and 34.

20 25 The lower ends of the three pistons are suitably secured to a cycle valve block 40, in turn secured to and within the slide 13.

30 35 The main piston has a longitudinal bore 41 and the auxiliary pistons each have a similar longitudinal bore 42. The cycle valve block has a longitudinal passage 43 connected by end branches 44 with the respective longitudinal bores 42 of the auxiliary pistons.

The valve block also has a longitudinal passage 45 in communication with the longitudinal bore 41 of the main piston.

40 45 The passages 43 and 45 are separated by a partition 46 having two valved passageways 47 and 48 connecting the passages 43 and 45, and controlled by spring seated valves.

The separation valve (Fig. 4)

45 50 The separation valve controls the passage 47, and has for its function to permit or prevent communication between the main cylinder and the auxiliary cylinders at different phases of the cycle of operation. The valve body 50 cooperates with a seat 51 in the passage 47. It has a spindle 52 extending in opposite directions and connected with pistons 53 and 54 in cylinders 55 and 56 formed in the valve block 40 on opposite sides of the main passages 43 and 45. The pistons 53 and 54 are of equal area, but the spindle 52 extends beyond the piston 54 in a shank 57 passing

through a stuffing box 58 and out of the cylinder 56.

A passage 60 running lengthwise to the valve spindle 52 maintains communication between the cylinders 55 and 56 on opposite sides of the pistons 53 and 54 and a crosswise passage 61 connects to the passage 60 with the passage 45, which, in turn, is in communication with the main cylinder. From this, it follows that whatever hydraulic pressure per square inch exists in the main cylinder will be transmitted to the cylinders 55 and 56 on opposite sides of the pistons 53 and 54. Those pistons are of equal cross section, but, because of the shank 57, they present unequal areas to the hydraulic pressure, and hence there is a tendency for the piston 53 to prevail over the piston 54 and open the separation valve. This tendency is resisted by a spring 67 in the cylinder 56 beneath the piston 54, and is, under appropriate conditions, to hold the valve closed.

When the hydraulic pressure in the main cylinder 27 reaches a predetermined amount, acting on the piston 53, it overcomes the resistance of spring 67 and opens the separation valve, thereby establishing communication between the main and auxiliary cylinders.

In one embodiment that has been found satisfactory, the power of the spring 67 is 10% above the hydraulic pressure created in the main cylinder when the pull-back force of the air pistons 14 is applied to the piston 28 only.

Opening the separation valve with air pressure

The shank 57, which projects through the stuffing box 58, becomes a piston rod 68 for a piston 69 in an air cylinder 70 supplied by pipe 71. By admitting sufficient air pressure to the cylinder 70, the separation valve will be open against the resistance of the spring 67, thus establishing free communication between the main and auxiliary cylinders. Conversely, by exhausting the air from the cylinder 70, the spring 67 will close the separation valve and cut off communication between the main and auxiliary cylinders.

The make-up valve

The make-up valve controls the passage 48 through the partition 46. The head 72 of the make-up valve closes with a seat 73 under the pressure of a spring 74, wound about a shank 75 and compressed between a spider 76 and an end wall 77 of a cylinder 78. Whenever the hydraulic pressure in the auxiliary cylinders is greater than in the main cylinder by a predetermined amount, it opens the make-up valve against the resistance of spring 74. In one embodiment that has been found satisfactory, the force of spring 74 is 10% above the hydraulic pressure generated in the auxiliary cylinders when the entire pull-back force of the pistons 14 is applied to the auxiliary pistons 34.

Air control for the make-up valve

The shank 75 of the make-up valve is reduced at 80, passes a stuffing box 81 and becomes the piston rod of a piston 82 and an air cylinder 83, receiving compressed air from a pipe 84. By admitting sufficient compressed air to the cylinder 83, the make-up valve is opened; and, conversely, by exhausting air from the cylinder 83 the make-up valve is allowed to close under the action of spring 74.

Slide limit stops (Fig. 1)

The slide 13 has arms 85 at each side, and directly above each arm is a stationary bracket 86 equipped with a threaded pin 87 having an enlarged head 88 at the bottom to form a stop against which the corresponding arm 85 comes to rest in the upper position of the slide. The pins being threaded into the brackets, the positions of the stops are readily adjustable. They are held in adjustment by lock nuts 89.

Filling and by-pass valve and pressure relief valve (Fig. 5)

The crown 12 forms a reservoir for hydraulic fluid into which the main and auxiliary cylinders project from the bottom. The auxiliary cylinder 32 is equipped with a filling and by-pass valve for controlling the flow of hydraulic fluid into and out of the system under selected conditions and also with a pressure relief valve to protect the system against excessive pressure.

The upper end of the auxiliary cylinder 32 is open at 90, and over this open end are bolted a flange 91 and a valve housing 92, the latter having wide ports 93 communicating with the reservoir of hydraulic fluid. The flange 91 is force-fitted with a valve seat 94 for a filling and by-pass valve 95 having guiding wings 96 and an upper end or head 97 projecting into the valve housing 92.

The valve 95 is urged toward its seat 94 by a compression spring 98 held against the shoulder 99 by spring retainer 100 threaded onto a sleeve 101, which, in turn, is threaded onto the head 97 of the valve 95.

When the piston 34 in the cylinder 32 descends, it produces a partial vacuum within that cylinder, and the atmospheric pressure in the reservoir compresses the spring 98 and opens the valve 95, permitting the hydraulic fluid to flow into the cylinder 32 and supply the vacuum. In this way, the valve performs the office of filling the system. In another way, it serves as a by-pass to permit the hydraulic fluid to flow freely back and forth between the system and the reservoir.

The valve 95 is hollow, and its lower portion is provided with a seat 102 for pressure relief or limiting valve 103, and provided with relief channels 104 above the seating line which communicate with drilled holes or passages 105 through the filling and by-pass valve 95.

Aligned with the sleeve 101 and abutting against its top end is a valve spindle 106 having in its lower end a cylinder 107 for a lapped piston sleeve 108, force fitted over a reduced end 109 of a valve stem 110 against a spring washer 111, and a valve spring 112 is compressed between that washer and the upper end of the valve 95. The valve spindle 106 extends upwardly into a hydraulic cylinder 114, and is solid above the cylinder 107 formed in its lower portion, and the cylinder 114 is provided with spaced stuffing boxes 115 fitted to the valve spindle. In the intermediate portion, the valve spindle 106 and the cylinder 114 are undercut to form a chamber 116, and the spindle is perforated at 117. The chamber 116 is connected by a pipe 118 with the lower end of the main cylinder 27.

When the hydraulic pressure in the main cylinder 27 increases to a predetermined amount, it is transmitted through the pipe 118 into the undercut portion 116, acts on the differential areas between the upper and lower portions of the valve spindle 106, and holds it firmly in its up position.

At the same time, this pressure is transmitted through the holes 117 into the cylinder 107 formed in the lower portion of the valve spindle and acts on the piston sleeve 108. The diameter of this sleeve is slightly larger than the effective area of the relief valve 103, and the net force created by the hydraulic pressure is on the differential area. When this force overbalances the spring 112, the relief valve will open and hydraulic fluid will exhaust through the drilled openings 105 in the ports 93 into the reservoir, relieving the pressure in the system. Since maximum pressure can be generated in the main cylinder 27 only when all the hydraulic cylinders are communicating through the separation valve 50, the pressure will be relieved in all hydraulic cylinders by the opening of the relief valve 103. The instant the pressure in the cylinders drops below the maximum predetermined amount, the spring 112 will close the relief valve.

Air control for the valves

The head 122 on the cylinder 114 includes a four-way air valve having a casing 130 with an air supply connection 131, exhaust connection 132 and two cylinder connections 133 and 133a. Within the valve casing 130 is reciprocating piston valve 134, provided with two ring ports 135 and 135a.

The valve spindle 106 is equipped at its upper end with piston 120 operating in air cylinder 121, closed by a head 122. The chamber underneath piston 120 is connected by channel 123 with one of the ports 133a of a four-way valve, and the chamber above the piston 120 is connected to the other port 133 of the four-way valve.

The reduced end 109 of the relief valve stem 110 extends upwardly above the face of the piston sleeve 108 to within a small distance from the lower face of the solid portion of the valve spindle 106.

When compressed air is admitted to cylinder 121 above the piston 120 at the same time, air is exhausted below the piston 120. Separation valve is open, and the hydraulic system has a pressure above a predetermined amount, this pressure acting on the differential area of the upper and lower portion of valve spindle 106 in the chamber 116 will overbalance the downward force of the piston 120.

When the pressure in the hydraulic system diminishes below a predetermined amount, the separation valve will close, and at the same time by means of pipe 118 the pressure in chamber 116 will also diminish to this predetermined amount. The downward force of piston 120 will overbalance this diminished hydraulic pressure acting on the differential area in valve spindle 106 in chamber 116, and the piston 120 and valve spindle 106 will move downward. The solid portion of the latter will strike the upper reduced end 109 of the relief valve stem 110, compress valve spring 112, and unseat the relief valve 103, thus relieving the hydraulic pressure in the cylinder. The piston 120 and valve spindle 106 will continue the downward movement until the lower face of the hollow portion of the valve spindle 106 strikes the open end of the sleeve 101, thereby compressing the valve spring 98, and unseating the filling and by-pass valve 95, thereby establishing free communication between the auxiliary cylinder 32 and the reservoir.

When the compressed air in the cylinder 121 above the piston 120 is exhausted through port 133, compressed air will simultaneously be ad-

mitted into the chamber below piston 120 in cylinder 121 through port 133a, and this will lift the piston 120 and valve spindle 106, and the valve spring 98 and 112 will close the filling and by-pass valve and the pressure relief valve.

The piston valve extends beyond the valve casing 130 at both ends; one end enters a hydraulic cylinder 136 and functions as a piston; and the other end passes through a guiding sleeve 137 and is connected with a bent rocking arm 138 pivoted at 139 to a cam guide post 140 inside the crown 12. The rocking arm 138 has a roller 141 cooperating with a cam 142, which is guided by the cam guide 140 and extends downwardly as a rod 143, equipped with a spring 144 and a collar 145 tending to move the rod and cam bar downwardly.

One of the arms 86 cooperating with the limit stops 88 is provided with an adjusting screw 146 rotatable by the handwheel 147 to adjust it to the proper height within the path of the cam rod 143 to lift the rod at a predetermined point in the up stroke of the slide 13 and disengage it at the same point in the down stroke of the slide.

The hydraulic pilot cylinder 136 is connected to a valve block 149 by a pipe 150. The valve block 149 is equipped with a balanced check valve 151, permitting free flow of exhaust from the cylinder 136 into the pipe 118 but blocking any flow in the opposite direction. It is also equipped with a balanced pressure relief valve 152, which permits flow from the pipe 118 into the cylinder 136 only when a predetermined pressure prevails in the pipe 118 but blocks any flow when the pressure is less than the predetermined amount, and also blocks any flow in the opposite direction; that is, from the cylinder 136 into the pipe 118.

This predetermined pressure is the hydraulic pressure generated in the main cylinder 27 when the entire pull-back force of the fluid pressure in the pistons 14 is applied to the main piston 28 only plus 50%. This occurs only at the beginning of the pressing stroke of the slide.

The slide adjustment (Fig. 3)

Mounted on the crown 12 is a small motor 160 driving a rotary pump 161 with a suction pipe 162 extending into the fluid space of the reservoir and a discharge pipe 163 connected to the inlet port of a solenoid operated three-way valve 164. The outlet of this valve is connected with the pipe 118, and through it with the main cylinder 27. The exhaust port 165 of the valve 164 leads back to the reservoir. The two solenoids 166 and 167 are connected with switches operated by push buttons 168 and 169.

When the button 169 is pressed, the solenoid 167 will shift the valve to connect the pipes 163 and 118, and the pump will then deliver fluid into the pipe 118 and the main cylinder 27, thereby forcing the slide 13 toward the bed. When the button 168 is pressed, the solenoid 166 connects to pipes 118 and 165 and allows hydraulic fluid to escape from the cylinder 27 to the fluid reservoir, and the slide increases its distance from the bed. This arrangement is used in adjusting the distance between the slide 13 and the bed to the required height for various sets of tools. Springs normally hold the valve 164 in mid position.

Slow-down arrangement (Figs. 2 and 4)

During the approach portion of the down

stroke, the slide 13 moves at three times the speed of the ram 26. If this speed should be maintained until the tool engages the work piece, the blow would be harsh. For that reason, it is desirable to change the speed of the approach portion of the down stroke into the speed of the drawing or pressing portion of that stroke just prior to contact of the tool with the work piece.

The pull-back cylinders 15 are supplied with compressed air by pipe 170. A small branch pipe 171 connects the supply pipe 170 with the inlet port of a solenoid operated three-way valve 172 through a telescoping joint 173. The solenoid valve is controlled by limit switch 174 mounted on the arm 85 of the slide alongside the valve. The outlet port of the valve 172 is connected by a pipe 175 with the air cylinder 70 of the separation valve 50. A stationary bar 176, carried by the side frame 11, is equipped with an adjustable cam 177 for cooperation with the limit switch 174. By adjusting this cam to operate the limit switch 174 just before the tool on the slide strikes the work piece, the solenoid valve is operated to admit air to the cylinder 70 and open the separation valve in time to slow the approach speed down to the drawing speed before the tool actually strikes the work piece, as hereafter explained. After the cam passes the limit switch, the valve exhausts the air from the cylinder 170 and leaves the further operation of the cycle to the hydraulic forces involved.

Elimination of the clutch (Fig. 2)

It is sometimes desirable, and in many cases entirely practical, to eliminate the air clutch 21 connecting the flywheel drive with the eccentric drive. This is accomplished by a special control for the filling and by-pass valve 95 and the make-up valve 72.

For this purpose, air is taken from the supply pipe 170 through a small pipe 180 to a telescoping joint 181 connected to the inlet port of a solenoid operated three-way valve 182 on another arm of the slide 13. The outlet port of the valve 182 is connected by a pipe 183 with the cylinder 83 of the make-up valve 72.

Another pipe 186 leads to the inlet port of a solenoid operated four-way air valve 187, one outlet 186a of which is exhaust into the atmosphere, and the other two outlets 184 and 185 connect to the exhaust port 132 and the supply port 131 of the valve 130 respectively.

During the normal operation of the press the solenoid operated valve 187 will be in a position to connect the exhaust port 132 of valve 130 through pipe 185 with the exhaust port 186a and the supply port 131 of valve 130 through pipe 184 with the inlet port 186.

The main shaft 23 for the eccentric 24 is equipped with a cam 188 engaging a limit switch 189 just prior to the instant that the eccentric 24 and the slide 13 reach the top position. Two push buttons 190 and 191 with their switches are mounted on the control panel of the press and are wired in series with the limit switch 189. Button 190 energizes the solenoids on valves 182 and 187, and button 191 de-energizes them. Pressing the button 190 produces no effect until the cam 188 strikes the limit switch 189, but then the make-up valve 72 and the filling and by-pass valve 95 are opened instantly, permitting free flow between the hydraulic cylinders and the reservoir. The slide 13 is arrested at top position, where it is held by the pull-back pistons 14, and the hydraulic fluid merely surges back and forth into and out of the reservoir as the ram reciprocates in the main cylinder 27. Pressing the button 191 de-energizes the solenoid valves, allows the valve 72 and 95 to close, and the operation of the press is resumed at the next down stroke of the ram 26.

When the press is idle, the air clutch 21 is open, the motor and flywheel with shaft 20 may be rotating, but the main shaft 23 and the eccentric 24 are standing still with the ram 26 in the main cylinder 27 in top position.

The pull-back pistons 14 in the cylinders 15 hold the tool carrying slide 13 in top position against the heads 88 of the pins 87, those pins having been adjusted to give the proper clearance between the faces of the slide 13 and the bed 10. The main and auxiliary pistons are all in top position.

The adjusting screw 146 holds the cam rod 143 with its cam 142 in top position, in which the roller 141 is engaged with the cam 142 and 25 is holding the piston valve 134 in position to connect the ring port 135 with the cylinder connection 133 and the exhaust port 132 and at the same time ring port 135a with the other cylinder connection 133a and the supply port 131. 30 This valve setting connects the air supply 131 through channel 123 with the chamber below piston 120 and connects the chamber above piston 120 with the air exhaust 132. The valve springs 98 and 112 are holding the filling and 35 by-pass valve 95 and the pressure relief valve 103 in closed position.

The hydraulic fluids in the entire system of cylinders and valves is free from pressure because the pull-back force of the pistons 14 is taken 40 entirely by the frame through engagement of the arms 85 with the heads 88 of the pins 87. The separation and make-up valves in the valve block 40 are closed.

The operation of the press is started by pressing 45 a push button on the control panel to engage the air friction clutch 21, start the countershaft 20 in rotation to drive the main shaft through the gearing 22, and start the eccentric and the ram on their downward stroke.

The fluid displacement in the main cylinder 27 caused by the downward movement of the ram 26 is locked within the cylinder 27 because 50 both the separation and make-up valves in the valve blocks 40 are closed. The total displacement caused by the ram is therefore communicated to the main piston 28 and through it to the slide 13, which starts its downward movement against the pull-back force of the pistons 14 in the cylinders 15. This creates a hydraulic pressure in the main cylinder 27 equal to the pull-back force divided by the cross-sectional area of the main piston 28.

The cross-sectional area of the ram 26 is equal 65 to the sum of the cross-sectional areas of the main piston 28 and the auxiliary pistons 34, or three times the cross-sectional area of the main piston 28. Consequently, since the displacement of the piston 28 must equal the displacement of the ram 26, the piston and the slide 13 must move three times as fast as the ram and three times the distance of the ram. This means 70 that, when the ram moves downwardly one inch, the main piston and the slide 13 must move downwardly three inches.

The auxiliary pistons 34 in the auxiliary cylin-

ders, being fastened to the slide by the valve block 40, accompany the main piston and the slide in their downward movement. This causes a partial vacuum or suction in the auxiliary cylinders 32 and 33, and atmospheric pressure in the reservoir, acting upon the effective area of the filling and by-pass valve 95, overcomes the valve spring 98 and opens the valve, allowing hydraulic fluid to flow from the reservoir into the auxiliary cylinder 32 and through the passages 43 and 44 in the valve block 40 into the auxiliary cylinder 33, filling the two cylinders continuously as the slide proceeds downwardly through the approach portion of the stroke.

The tool carried by the slide 13 strikes the metal to be worked, and resistance against further movement is encountered. The force required for further downward movement manifests itself as an increase in hydraulic pressure in the main cylinder 27, and when that increase reaches a predetermined amount (10% above the prevailing pressure of the previous moment) it overbalances the valve spring 67, and the separation valve 50 opens, providing communication between the passages 43 and 45 in the valve block and hence between the main cylinder 27 and the auxiliary cylinders 32 and 33 through their bored pistons 34. The opening of the separation valve terminates the vacuum or suction in the auxiliary cylinders instantaneously, and the filling and by-pass valve 95 closes immediately, thereby blocking the flow between the auxiliary cylinder 32 and the reservoir.

During this initial downward movement of the slide 13, adjusting screw 146 and with it the rod 143 and the cam block 142 move downwardly until the collar 145 comes to rest against the stationary bracket 86 and the cam 142 has released the roller 141 on the bent rocking arm 138.

The ram 26 continues downwardly, but its displacement is now distributed equally to the three cylinders; and, since its displacement equals the total displacement of the main and auxiliary pistons, the slide moves downwardly at the same speed and for the same distance as the ram.

The further downward movement of the tool carried by the slide deforms the metal being worked and meets increasing resistance. This is continually being overbalanced by the driven eccentric 24 through the ram 26, which increases the hydraulic pressure in the three cylinders. This pressure is transmitted from the main cylinder 27 through the pipe 118 to the chamber formed by the undercut 116 in the valve spindle 106 within the cylinder 114 and to the relief valve 152 in the valve block 149.

When the pressure reaches a predetermined amount (hydraulic pressure generated when the entire pull-back force is applied to the main piston 28 plus 50%) the relief valve 152 opens and allows the hydraulic fluid to pass through the pipe 150 into the cylinder 136 and shift the reciprocating piston valve 134 to the right (it being free to move as the cam 142 is out of the way of the roller 141) into a position connecting air supply 131 with cylinder connection 133, thereby admitting compressed air into the chamber above piston 120, and at the same time connecting air exhaust 132 with the port 133a and channel 123, thereby exhausting the compressed air in the chamber below piston 120 in cylinder 121. The force of that piston thus created is greatly overbalanced by hydraulic pressure in the chamber formed by the undercut 116 and the holes 117, so that no movement of the spindle 106 takes place.

The slide and tool continue downwardly until the eccentric has revolved 180 degrees from the start, when the lowest point is reached, at which the worked metal has conformed to the contours of the tools. At this point, the hydraulic pressure has increased to the highest limit, and the frame structure is highly stressed. Further movement of the eccentric raises the ram 26 in the main cylinder 27 in a gradual manner, thereby gradually relieving the hydraulic pressure in the main and auxiliary cylinders and also the stress in the press frame structure until the pressure has decreased to an amount (total pull-back force of the pistons 14 divided by the sum of the areas of the three pistons, or the area of the ram, plus 10%). During this gradual decline in pressure, it passes a value (total pull-back force divided by the area of the piston 28 plus 10%), at which point the valve spring 67 seats the separation valve 50 and cuts off communication between the passages 43 and 45, thereby separating the main cylinder 27 from the auxiliary cylinders 32 and 33.

Simultaneously, the force on the differential area between the upper and lower portions of the valve spindle 106 in the cylinder 114 has decreased in like manner, and is overbalanced by the force of the air pressure on the area above the piston 120, and that piston with its spindle 106 moves downwardly into contact with the upper end 109 of the valve stem 110, overcoming spring 112 and opening the relief valve 103, thereby establishing a restricted communication between the auxiliary cylinders and the reservoir and relieving the hydraulic pressure in them.

The downward movement of the piston 120 and the spindle 106 continues, and the lower end of the latter pushes down the sleeve 101, compressing the valve spring 98 and opening the filling and by-pass valve 95, thereby establishing free communication between the auxiliary cylinders and the reservoir. The downward movement of the piston 120 is limited by the stop provided in the cylinder 121.

This operation of the valves 95 and 103 is effected very quickly, and they remain open as long as the air pressure in the cylinder 121 above the piston 120 prevails.

The ram 26 in the main cylinder 27 with the slide and the three pistons now move upwardly. The hydraulic pressure in the main cylinder 27 is the total pull-back force of the pistons 14 divided by the cross-sectional area of the pistons 28, and the displacement of that piston must equal the displacement of the ram 26. Because the area of the piston and ram are in the ratio of 1:3, the piston 28 moves three times the speed and three times the distance the ram 26 moves. Thus, when the ram rises one inch, the piston 28 and the slide will rise three inches. The displacements of the two auxiliary cylinders are forced through the filling and by-pass valve 95 into the reservoir.

At a predetermined point in this upstroke, the adjusting screw 146, carried by the arm 85 on the slide, strikes and lifts the lower end of the rod 143, lifting the cam 142, shifting the roller 141, and with it the arm 138 and the reciprocating valve 134 to the left into a position connecting air exhaust 132 with cylinder connection 133, thereby relieving the pressure in the chamber above piston 120 and at the same time connecting air supply 131 with the port 133a and channel 123, thereby admitting compressed air into the chamber below piston 120 in cylinder 121,

11

raising piston 120 and valve spindle 106, relieving the pressure on the springs 112 and 98, and permitting the filling and by-pass valve 95 and the pressure relief valve 103 to close.

The adjusting screw 146 is set to cause the exhaust of air above the piston 120 and have the filling and by-pass valve 95 and pressure relief valve 103 close when the slide passes through the point a distance from its top position equal to the length of the pressing portion of the stroke, the valves 95 and 103 being closed and the separation valve 50 blocking communication between the main and auxiliary cylinders. The fluid in those cylinders is locked while the ram 26 continues upward, thereby producing a partial vacuum or suction. The hydraulic pressure in the auxiliary cylinders 32 and 33 is the total pull-back force of the pistons 14 divided by the combined area of the auxiliary pistons 34; and this pressure, acting in the passage 43 of the valve block 40, overbalances the make-up valve spring 74 and opens the make-up valve 72, permitting the hydraulic fluid in the auxiliary cylinders to flow into the main cylinder. The upward movement of the ram and the flow of the fluid continues until the slides strike the heads 88 of the pins 87 in the stationary brackets 86. This ends one stroke cycle with the press being in the initial position before the cycle started.

When the press is adjusted for single cycle operation, the slide 13, just before contacting the heads 88, trips a limit switch, which de-energizes the solenoid operated air valve and opens the clutch 21. This stops the eccentric and the slide while the motor and flywheel continue rotating.

From the above description of the operating cycle, it will be seen that the slide has a variable stroke. When the slide encounters no work resistance—that is, when the press is operated idly without a set of tools—the separation valve remains closed and the entire displacement of the ram 26 changes into displacement of the main piston 28. The strokes of the piston 28 and the slide 13 are therefore three times the stroke of the ram 26. Hence, if the eccentric stroke is six inches, the slide stroke is eighteen inches. But, if the slide should encounter resistance at the very start of the stroke, the separation valve would immediately open communication between the main and auxiliary cylinders, and the displacement of the ram 26 through its entire stroke of six inches would distribute itself equally among the three cylinders and give the slide a stroke of six inches. In between those limits of six inches minimum and 18 inches maximum, any length of stroke can be produced by placing the point of contact of the slide tool with the work piece in the proper relation to the total length of the stroke of the slide.

Each down stroke consists of an approach stroke plus the pressing stroke or drawing stroke. The latter requires the equivalent length of stroke of the ram and eccentric. The length of the approach stroke is three times the remaining length of the ram and eccentric. The approach stroke must be long enough to allow the removal of the work piece from between the work engaging tools.

In the conventional, presently used press, the length of the stroke of the slide is fixed, and is the equivalent of the stroke of the driving crank or eccentric, commonly 10 inches. This difference in the stroke of the eccentric of 10 inches on the conventional, presently used press and 6 inches on the press of this invention is the crux of it. This difference in eccentric represents a

12

very substantial saving in the cost of construction of the press, amounting to a great deal in large presses with long strokes. For instance, a conventional press with a crank or eccentric of 42-inch stroke can be replaced by this invention with a crank or eccentric of 27-inch stroke, or a difference of 15 inches.

Increase in number of stroke cycles per minute

10 But more important than the saving in cost of construction just mentioned and perhaps the most important feature of the invention is that it increases the number of stroke cycles per minute beyond anything possible with conventional types of presses.

15 In the conventional press having a crank or eccentric stroke of 10 inches, the work angle is 72° 30' as compared with a press embodying the present invention having an eccentric stroke of 6 inches and a work angle of 104° 30'.

20 Each metal used in forming work pieces in presses has its own definite limit of speed in inches per minute at which it may be deformed by the tools without rupturing. Higher speeds than this limit will tear the metal and spoil the work piece.

25 Assuming a conventional press with a 10-inch stroke operates at 12 stroke cycles per minute, based on the pressing speed for the particular material, then the work angle of 72° 30' is made in approximately one second. Since the limit of working speed must be maintained, the work angle of 104° 30' of the press embodying the present invention must be made in the same interval of one second. This means that the eccentric of such a press makes one revolution or one complete stroke in 3.5 seconds, or operates with a speed of 17 strokes per minute as compared with 12 strokes per minute for the conventional press, an increase of 40%.

30 There are, however, pressing operations in which the labor cost involved precludes the possibility of taking advantage of this increased number of strokes per minute. But another advantage may be had by running the press embodying this invention at the same number of strokes per minute as the conventional press. Under these conditions, the work angle of 104° 30' will be made at the same angular speed as the work angle of 72° 30' of the conventional press, or in 1.44 seconds, or an increase of work time of about 44%.

35 It is the general experience of men in the industry that the slower the pressing speed, the better the formation of the work piece and the smaller the percentage of loss due to rejects. Consequently, the press of this invention, running at the same number of strokes per minute as the conventional press, will maintain the production rate but give better results and fewer rejects.

Advantage of the improved slide adjustment

40 The slide adjustment in a press is necessary to vary the height of the opening between the top of the bed and the face of the slide when the slide is in its lowest position, ordinarily termed the "shut height," meaning the vertical overall dimension of the tool set when in closed position. Hence, there must be an adjustment for each tool set having a different overall vertical dimension. In a conventional press with a 10-inch eccentric stroke, an 8-inch minimum and 14-inch maximum shut height requires an adjustment of 6 inches. As compared with this,

a press embodying the present invention, but having a 6-inch eccentric with a maximum shut height of 14 inches, has a minimum shut height of 8 inches without any adjustment.

The adjusting mechanism of the conventional press consists of a heavy screw or screws between the slide and the driving device. They must be constructed to resist the full pressure of the machine, and the industry requires presses from a capacity of 75 tons to many hundreds or even thousands of tons, which makes the adjusting mechanism very costly. As compared with this, adjustment with the present invention is made by the simple means described heretofore under the heading "The Slide Adjustment." Increasing the volume of fluid in the hydraulic system decreases the shut height. Decreasing the volume increases the shut height; and the increase and decrease are controlled entirely by the push buttons 168 and 169. The adjustment not only provides for quick and very accurate setting of the shut height to conform to a tool set, but controls the maximum pressure produced on a tool set and provides for a dwell of pressure on the work piece at the bottom of the stroke.

Fine pressure control

A press embodying the present invention should be equipped with a hydraulic pressure gauge 200 connected to the hydraulic system—for instance, by a pipe 201 leading to the pipe 118 or some other part in communication with the interior of the main cylinder 21. Such a gauge indicates the pressure prevailing in the system and the total pressure generated in the press.

The conventional press has no equivalent means. The adjustment depends entirely on the judgment and experience of the operator. The quality of the work pieces made depends greatly on the pressure, and as a result conventional presses are frequently adjusted higher than actually required, and many times the over-adjustment results in destruction of the press. In contrast, the operator of the press embodying the present invention merely has to observe the pressure gauge 200 and operate one or both of the push buttons 168 and 169 to make the pressure delivered exactly what is desired. He can do this while the press is operating.

Introducing a pressure dwelling period at the bottom of a stroke

It is well known that a time interval of steady pressure on the work piece after it is pressed sets the work metal and permits the internal stresses to arrange themselves in a balanced condition. Work pieces formed in that manner have the true and accurate contours of the tools without warps or other undesirable deformations. The conventional press has no means for producing such a dwell. Consequently, the work pieces frequently have to be fitted by hand.

The present invention makes it possible to introduce a pressure dwelling period at the bottom of the stroke up to 30° eccentric angle without interrupting the stroke cycle. The operator simply adjusts the top position of the slide to bring it to rest against the stops 33 before the eccentric and ram have reached their top positions. The additional movement of the ram creates a partial vacuum or suction, which is satisfied with fluid admitted through the filling and by-pass valve 95. On the next down stroke, this additional fluid brings the slide to the bottom of

its travel before the ram reaches the bottom of its stroke and produces the dwell while this additional fluid is exhausted from the system through the pressure relief valve, during which the tools are held pressed against the work piece.

Relieving a jammed press

When the working stroke of a press absorbs the energy of a flywheel excessively to such an extent that the circuit breakers cut off the power, the press with its entire structure is severely overstressed. To free the press from such a condition is a lengthy and costly procedure. Frequently the dies and tie rods must be torch-cut. With a press of the present invention, when a jam occurs it may be relieved in a matter of seconds by operating the push button control to decrease the fluid in the system.

The gist of the invention lies in introducing between the drive with a fixed stroke and the slide a hydraulic transmission including means for delivering different portions of the displacement of the ram to the piston during different portions of the stroke. The above-mentioned and other advantages are inherent in this feature.

The embodiment here used for illustration, including one main and two auxiliary cylinders, appears to be the best for wide presses and heavy duty; but engineers will readily design other embodiments for particular conditions and to suit personal preferences in which the number of cylinders and their arrangement and relative size of pistons will be varied. Some will prefer to use but a single cylinder for the ram and a piston connected with the slide. Others will prefer to use one or more auxiliary cylinders. The principles here illustrated readily lend themselves to those and other variations.

What have here been called "separation valve," "make-up valve," etc., are so called because of the arrangement in this embodiment. In other embodiments, they may be merely valves.

I claim:

1. In a press, a slide, a mechanical drive having a fixed stroke and a hydraulic transmission for transmitting force through a fluid between the slide and the drive including a ram operated by said drive, main and auxiliary cylinders with pistons, a fluid connection between the ram and main cylinder, a fluid reservoir, a fluid connection between the cylinders, a fluid connection between the auxiliary cylinder and the reservoir, and spring seated valves for controlling fluid communication through said connections, the valve in the reservoir connection permitting fluid flow from the reservoir to the auxiliary cylinder when the pressure of the auxiliary cylinder is below that of the reservoir by a predetermined amount, and the valve in the cylinder connections permitting flow from the main cylinder to the auxiliary cylinder upon a predetermined excess of pressure in the main cylinder.

2. In a press, a slide, a mechanical drive having a fixed stroke and a hydraulic transmission for transmitting force through a fluid between the slide and the drive including a ram operated by said drive, main and auxiliary cylinders with pistons, a fluid connection between the ram and main cylinder, a fluid reservoir, a fluid connection between the cylinders, a spring seated valve for said connection yielding to pressure in the main cylinder, a second spring seated valve for said connection yielding to pressure in an auxiliary cylinder, a fluid connection between the

auxiliary cylinder and the reservoir, a spring seated valve for said last mentioned connection yielding to vacuum in said auxiliary cylinder, and means to open said last mentioned valve in response to pressure developed in said main cylinder.

3. In a press, a slide, a mechanical drive having a fixed stroke and a hydraulic transmission for transmitting force through a fluid between the slide and the drive including a ram operated by said drive, main and auxiliary cylinders with pistons, a fluid connection between the ram and main cylinder, a fluid reservoir, a fluid connection between the cylinders, a spring seated valve closing said fluid connection during the approach movement of the slide and automatically opened by increased pressure in the main cylinder, a fluid connection between an auxiliary cylinder and the reservoir, and a spring seated valve for said last mentioned connection yielding to vacuum in said auxiliary cylinder and to pressure in said main cylinder.

4. In a press, a slide, a mechanical drive having a fixed stroke and a hydraulic transmission for transmitting force through a fluid between the slide and the drive including a ram operated by said drive, main and auxiliary cylinders with pistons, the area of the ram being equal to the combined areas of the pistons, a fluid connection between said ram and main cylinder, a fluid reservoir, a fluid connection between the cylinders, a fluid connection between an auxiliary cylinder and the reservoir, and spring seated valves for said connections, the valve in the reservoir connection permitting fluid flow from the reservoir to the auxiliary cylinder when the pressure of the auxiliary cylinder is below that of the reservoir by a predetermined amount, and the valve in the cylinder connections permitting flow from the main cylinder to the auxiliary cylinder upon a predetermined excess of pressure in the main cylinder.

5. In a press, a slide, a mechanical drive having a fixed stroke and a hydraulic transmission for transmitting force through a fluid between the slide and the drive including a ram operated by said drive, main and auxiliary cylinders with a piston in each, a fluid connection between the ram and main cylinder, a fluid connection between the cylinders, and means for closing the connection during the approach movement of the slide and opening the connection during the drawing movement of the slide.

6. In a press, a slide, a mechanical drive having a fixed stroke at least the draw portion of which approximates simple harmonic motion and a hydraulic transmission between the slide and the drive including automatic means for positively moving the slide at a speed in excess of the drive during the approach portion of the stroke, and then moving the slide at a slow speed and with substantially harmonic motion during the draw portion of the stroke.

7. In a press, a slide, a mechanical drive having a fixed stroke and a hydraulic transmission for transmitting force through a fluid between the slide and the drive including a ram operated by said drive, main and auxiliary cylinders with a piston in each, a fluid connection between the ram and main cylinder, and means for delivering all the displacement of the ram against the main piston during the approach movement of the slide and against all the pistons during the drawing movement of the slide.

8. In a press, a slide, a mechanical drive having

a fixed stroke and a hydraulic transmission for transmitting force through a fluid between the slide and the drive including a ram operated by said drive, main and auxiliary cylinders with pistons, a fluid connection between the ram and main cylinder, a fluid reservoir, a fluid connection between the cylinders, a fluid connection between an auxiliary cylinder and the reservoir, and automatic separation and make-up valves for said connection, said separation valve adapted to control fluid connection from the main cylinder to the auxiliary cylinder in response to a predetermined pressure differential therebetween.

9. In a press, a slide, a mechanical drive having a fixed stroke and a hydraulic transmission for transmitting force through a fluid between the slide and the drive including a main cylinder, a main piston, a ram in the main cylinder operated by said drive, a fluid connection between the ram and the main cylinder, auxiliary cylinders, an auxiliary piston in each auxiliary cylinder, a fluid connection between the main cylinder and the auxiliary cylinder, and means for blocking communication between the main cylinder and the auxiliary cylinders during the approach movement of the slide and connecting them during the drawing movement of the slide.

10. In a press, a slide, a mechanical drive having a fixed stroke and a hydraulic transmission for transmitting force through a fluid between the slide and the drive including a ram operated by said drive, main and auxiliary cylinders, a fluid connection between the ram and main cylinder, a hollow piston in each, a valve block connecting the hollow pistons, and automatic separation and make-up valves in the valve block, said separation valve adapted to control fluid communication between said main and auxiliary cylinders.

11. In a press, a slide, a mechanical drive having a fixed stroke and a hydraulic transmission for transmitting force through a fluid between the slide and the drive including a ram operated by said drive, main and auxiliary cylinders, a fluid connection between the ram and main cylinder, a hollow piston in each, a valve block connecting the hollow pistons, a fluid connection in the block for the main piston, a fluid connection in the block for the auxiliary pistons, and automatic separation and make-up valves in the block for said connections, said separation valve adapted to control fluid communication between said main and auxiliary cylinders.

12. In a press, a slide, a mechanical drive having a fixed stroke and a hydraulic transmission for transmitting force through a fluid between the slide and the drive including a ram operated by said drive, main and auxiliary cylinders, a fluid connection between said ram and main cylinder, a hollow piston in each, a valve block connecting the hollow pistons, a fluid connection in the block for the main piston, a fluid connection in the block for the auxiliary pistons, automatic separation and make-up valves in the block for said connections, and means for operating said valves, said separation valve adapted to control fluid communication between said main and auxiliary cylinders.

13. In a press, a slide, a mechanical drive having a fixed stroke and a hydraulic transmission for transmitting force through a fluid between the slide and the drive including a ram operated by said drive, a cylinder, a piston in the cylinder, a fluid connection between the ram and the cyl-

inder, a fluid reservoir, a pump, fluid connections, and valve means to direct the fluid from the pump to the cylinder and from the cylinder to the reservoir.

14. In a press, a slide, a mechanical drive having a fixed stroke and a hydraulic transmission for transmitting force through a fluid between the slide and the drive including a ram operated by said drive, a cylinder, a piston in the cylinder, a fluid connection between the ram and the cylinder, a fluid reservoir, a pump, fluid connections, valve means to direct the fluid from the pump to the cylinder and from the cylinder to the reservoir, and push button controls for said valve means.

15. In a press, a slide, a mechanical drive having a fixed stroke and a hydraulic transmission for transmitting force through a fluid between the slide and the drive including a ram operated by said drive, main and auxiliary cylinders with a piston in each, a fluid connection between said ram and main cylinder, means for driving all the displacement of the ram against the main piston during the approach movement of the slide including a fluid connection between the cylinders, a separation valve automatically closing the connection, and means for opening the valve toward the end of the approach movement.

16. In a press, a slide, a mechanical drive having a fixed stroke and a hydraulic transmission for transmitting force through a fluid between the slide and the drive including a ram operated by said drive, main and auxiliary cylinders with pistons, a fluid connection between the ram and main cylinder, a fluid reservoir, a fluid connection between the cylinders, a spring seated valve for said connection yielding to pressure in the

main cylinder, a fluid connection between an auxiliary cylinder and the reservoir, a spring seated valve for said last mentioned connection yielding to vacuum in said auxiliary cylinder and to pressure in said main cylinder, and adjustable means for stopping the upward travel of the slide before the ram reaches the top of its stroke.

17. In a press, a slide, a mechanical drive having a fixed stroke and a hydraulic transmission for transmitting force through a fluid between the slide and the drive including a cylinder, a ram in the cylinder connected with the drive, a fluid connection between the ram and cylinder, a piston connected with the slide, and means including valves for delivering different portions of the displacement of the ram to the piston during different portions of the stroke.
